UNITED STATES PATENT OFFICE.

SAMUEL BRUNT, OF SEBRING, OHIO, ASSIGNOR TO THE SEBRING MANUFACTURING CORPORATION, OF SEBRING, OHIO.

DESIGN FOR A SUGAR BOWL.

Application filed April 27, 1927. Serial No. 21,764. Term of patent 7 years.

To all whom it may concern:

Be it known that I, SAMUEL BRUNT, a citizen of the United States, residing at Sebring, in the county of Mahoning and State of Ohio, have invented a new, original, and ornamental Design for a Sugar Bowl, of which the following is a specification, reference being had to the accompanying drawing, forming part thereof.

Fig. 1 is a side elevation of the sugar bowl, showing my new design.

Fig. 2 is a plan view of said sugar bowl.

I claim:

The ornamental design for a sugar bowl, as shown.

SAMUEL BRUNT.
